ILLUMINABLE HOLDER FOR A TELEPHONE AND WRITING PAD

Leonard S. Youngs, 5903 Watt Ave.,
North Highlands, Calif.

Filed Aug. 10, 1965, Ser. No. 86,521

Term of patent 14 years

(Cl. D74—1)

FIG. 1

FIG. 2

FIG. 3

FIG. 4

FIG. 5

I claim:

The ornamental design for an illuminable holder for a telephone and writing pad, as shown.
